US00D787083S

(12) **United States Design Patent** (10) **Patent No.:** **US D787,083 S**
(45) **Date of Patent:** **** May 16, 2017**

(54) **LIGHT-BASED DERMATOLOGIC TREATMENT DEVICE**

(71) Applicant: **Shaser, Inc.**, Lexington, MA (US)

(72) Inventors: **Douglas Ely**, North Andover, MA (US);
Bikram Yonjan, Somerville, MA (US);
Bernhard Schroter, Upton, MA (US);
William Owens, Framingham, MA (US);
Daniel Roth, Newton, MA (US)

(73) Assignee: **SHASER, INC.**, Lexington, MA (US)

(**) Term: **15 Years**

(21) Appl. No.: **29/551,724**

(22) Filed: **Jan. 15, 2016**

Related U.S. Application Data

(63) Continuation-in-part of application No. 29/434,358, filed on Oct. 12, 2012, now abandoned.

(51) **LOC (10) Cl.** **28-03**

(52) **U.S. Cl.**

USPC **D24/209**

(57) **CLAIM**

The ornamental design for a light-based dermatologic treatment device, as shown and described.

DESCRIPTION

FIG. 1 is a front view of the dermatologic treatment device showing the new design.

FIG. 2 is a side view thereof.

FIG. 3 is a back view thereof.

FIG. 4 is an isometric side view thereof.

FIG. 5 is a top view thereof.

FIG. 6 is a bottom view thereof.

FIG. 7 is a perspective view thereof.

FIG. 8 is an exploded perspective view thereof; and,

FIG. 9 is an opposite side elevated exploded perspective view in closer detail.

1 Claim, 9 Drawing Sheets
